GEORGE H. SETHMAN, OF DENVER, COLORADO, ASSIGNEE, BY DIRECT AND MESNE ASSIGNMENTS, TO THE ELECTRIC RESEARCH COMPANY, OF DENVER, COLORADO, A COMMON LAW TRUST.

ELECTRIC FURNACE AND METHOD OF OPERATING THE SAME.

Application filed January 30, 1922. Serial No. 532,787.

To all whom it may concern:

Be it known that I, GEORGE H. SETHMAN, a citizen of the United States, residing at the city and county of Denver and State of Colorado, have invented certain new and useful Improvements in Electric Furnaces and Methods of Operating the Same; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to the art of smelting refractory ores, and has special reference to an electrically operated furnace employing single or polyphase current of a certain characteristic wave form.

It has long been recognized that an electric furnace for smelting refractory metaliferous ores would possess many advantages over the present extensively employed method of using a blast furnace provided with coke fuel. I am aware that many types of electrically operated furnaces have been designed and patented and that some of them are successfully employed in smelting highly conductive ores, such as iron ores, but so far as I am aware, there has not been produced an electric furnace which will successfully smelt the highly refractory auriferous, auriargentiferous, plumbiferous and other highly refractory ores which have little or no electrical conductivity as compared with the highly conductive iron ores.

Attempts to employ an electric arc furnace for smelting the above type of ores have usually been followed by disastrous results, owing primarily to the fact that the resistance of the arc path is subject to the most violent fluctuations, varying from a very high resistance to a dead short circuit. In order to successfully operate an arc under such variable conditions by means of the ordinary direct or alternating current, it is necessary to equip the furnace with complicated regulating means which will automatically vary the voltage in an attempt to keep the current strength constant. Such regulating means are not reliable in operation, with the result that troublesome surges, "kick-backs," and intermittent disturbances

take place, which damage the generators and transformers and make it a practical impossibility to carry out the smelting successfully.

I have found that if I employ, as the source of electric current supply, a generator which generates a flat top expanding wave, due to the fact that at no time after the first part of the voltage and current waves are produced is there any dynamic action between the fields and the armature, that in a circuit supplied with current by such a generator, extreme variations in the arc resistance and even short circuits can take place without injuring the generator, blowing fuses, opening circuit breakers, throwing off the belts on belted units, or distressing the engine or generator, in the case of units of the direct connected type. It is the employment of the above type of current generator that has enabled me to successfully smelt highly refractory ores without employing any regulating devices whatever for the purpose of compensating for the variations in the arc resistance, and without a source of current supply having the above characteristics, an electric arc furnace for smelting this class of ores is not regarded as commercially practicable.

In order to describe my invention with the greatest degree of clearness, I shall have reference to the accompanying drawing, in which—

Fig. 1 is a diagram showing the characteristic voltage and current wave produced by the generator which I employ in this smelting process;

Fig. 2 is a diagram showing how a three-phase Y connected source of current supply is connected to the smelter electrodes;

Fig. 3 is a vertical longitudinal section of one form of smelter employed by me; and

Fig. 4 is a longitudinal section of a portion of a modified form of smelter.

The same reference characters will be used to represent the same parts throughout the several views.

In Fig. 1, O—X represents the abscissa and O—Y the ordinate axis with respect to which I have plotted the potential curve E and the current curve C, which have the characteristics which I consider as essential to the successful operation of my smelter.

Considering O as the point of origin, curve E extends upwardly in a direction which corresponds somewhat to that which would be followed by an ordinary sine curve 5 until the point D is reached when it becomes parallel to the longitudinal axis O—X for a short time until the point F is reached. At this point all dynamic action between the armature and the fields of the generator ceases and the voltage curve extends downwardly to the axis on a line that corresponds to a logarithmic curve. The current curve C follows the general shape of the voltage curve E and attains its zero 10 value at the same instance as the voltage curve. In case of a low arc resistance or dead short circuit, no serious damage can result when a generator producing a potential curve of the above described type 15 is employed, for the reason that during the part of the curve from O to D the value of the current is limited by the counter electromotive force of self induction, while after the point F is passed, the electromotive 20 force is merely that which is due to the inductive kick or stored energy of the windings.

In Fig. 2 I have shown a source of three-phase supply G in which the phases a, b 30 and c are connected Y fashion. The neutral point of the generator is connected by means of a conductor 2 with a plate electrode 3 which is located in the bottom of the furnace. The free ends of the respective phases a, b 35 and c are connected respectively with electrodes 4, 5 and 6 by means of conductors 7, 8 and 9. I have shown a three-phase supply because this is the simplest and serves to illustrate the arrangement as well as any 40 other number of phases, but I desire to point out that it is my intention to employ any number of phases desired, as for example, two, three, six, nine and twelve, the exact 45 number being dependent on the size of the smelter and other elements which will determine the design of the layout.

In Fig. 3 I have shown one form of furnace which I consider well adapted for use 50 in carrying out my method. The furnace 10 is built of fire brick or any suitable refractory substance, and has its base portion 11 enlarged to some extent; the upper part of 55 the furnace has a cylindrical opening 12 therein which terminates at the bottom in an enlarged furnace space 13, in the bottom of which is formed a pocket or depression 14 within which is placed a copper plate 3 whose upper surface is provided with a number of copper points 15. The pocket 14 is 60 filled with graphite so as to form a conductive protective cover for the copper electrode 3. Projecting through the inclined walls 17 of the furnace 10 are a plurality of electrodes, the exact number of which depends 65 on the number of phases employed; these

electrodes are equally spaced and when three are employed, as in the example illustrated, they are spaced 120 degrees apart. Where the electrodes enter the furnace, they pass through stuffing boxes 18 which are preferably hollow and adapted to be cooled by the circulation of water through the hollow interior thereof. The electrodes are slideable in the boxes 18 so as to permit of adjustment 70 being made.

The chamber 18 is provided near the bottom thereof with two spouts 19 and 20, the former of which is located near the bottom of the chamber and serves for removing the matte, while the spout 20 is located somewhat higher and serves for removing the slag, the separation of the slag and matte being effected by the action of gravity which causes the matte, which is heavier, to sink to the bottom of the liquid mass. Near the top of the furnace I provide a hollow conduit 21 which extends to and is connected with a condenser (not shown). The top of the furnace is covered by a plate 22, which is provided centrally thereof with a cylindrical member 23 of considerable length, the lower end of which projects into the furnace and is provided with a closing cone 24, which is pivotally connected to one end of pivotally mounted lever 25, on the outer end of which 80 is a weight 26. The ore is fed to the furnace through the tube 23 in the well known manner. On the sides of the furnace I have provided several hoppers 27 which can be employed for adding material to the furnace. If it should be found desirable, fuel 85 may be added to the ore through hoppers 27 and used to increase the preheating effect. Line 28 indicates the proper level of ore in 90 the furnace.

In Fig. 4 I have shown a slightly modified form of furnace, which differs from the one described above, mainly, in this, that a considerable space is provided between the lower edge of the opening of the matte spout and the top of the graphite packing 16, which space is designed to contain the molten lead, which may be removed from time to time through opening 29, or which may automatically overflow over edges 30 whenever it exceeds the level of this edge.

Although I have shown and described in detail a furnace structure, it is evident that furnaces of different forms may be employed with my particular current supply. 110 The furnace described above is, however, a satisfactory and practical device, and I reserve the right to protect the same in this or in a divisional application.

The operation of my furnace is as follows: 115 The electrical connections are formed as indicated on the drawing and explained above. An electrically conducting ore or other electrically conducting material is then placed in the furnace and about and between elec- 120

trodes 4, 5, 6, and 16, so that when the electromotive force is applied, current will begin to flow between the electrodes. Ore and fluxes are then introduced into the furnace 5 in the proper proportions and in such amounts as desired, not extending above line 28. The current is then applied and flows through the conducting material from the several electrodes to plate 3. The current 10 flowing through the conductive material causes the latter to become intensely heated and very soon melts the same, after which the arc having become established continues to burn and heat the refractory ores that 15 feed down from above. The ore as it comes down carries a small portion of the current, as it is not an absolute non-conductor, and heat is therefore generated by the current flowing through the material as well as by 20 the arc. Both forms of heat are therefore generated and utilized in the reduction. When the condenser is attached and operated, a strong fan (not shown) will be in operation and arranged to suck the gases 25 from the furnace through pipe 21, and the hot gases from around the arc will pass upwardly, roasting and preheating the ore so that by the time it reaches the arc chamber 13 it will be heated to very near the melting 30 point. By having the chamber 12 of sufficient length, the gases may be cooled to a comparatively low degree before they leave the furnace, thus assuring a very thorough utilization of all the heat generated. The 35 spouts 19 and 20 may be left open so that the slag and matte may flow from the furnace as fast as they are formed, thus providing for continuous operation.

My smelting furnace can be made of any 40 desired size and capacity, and small units can be cheaply and easily constructed. It therefore becomes possible for mines that are located far from a railroad or a fuel supply to be equipped with electric smelters, 45 the current for the operation of which can be supplied by an internal combustion engine driving one of my specially designed generators referred to above. As fuel for the operation of the engine can be readily transported, it is apparent that mines that heretofore have been idle owing to the excessive 50 cost of transporting the ore to a smelter, can be operated, and the ore smelted electrically. The matte can then be sent to a refinery 55 where it can be separated into the several metals of which it is composed. Large custom smelters can also be operated as described above, and at a cost per ton of ore greatly less than what it is with the present 60 coke blast furnace.

As pointed out above, I do not claim to be the first one to have employed electricity for smelting ores, but I do claim that I have discovered the proper form of potential and current wave to be employed in the suc-

cessful operation of a smelting furnace for refractory ores, and I therefore consider that I am the inventor of the combination of an electric generator producing this specific form of current wave and an electric 10 arc furnace, as the two cooperate to produce a result long desired and often sought but never before attained.

The voltage will be anything that may be found necessary to produce the arc between 75 the electrodes and the bottom plate 3, and ordinarily it is about 145 volts, while the amperage will run from 250 in small furnaces to several thousand amperes in the larger furnaces. The frequency is also more 80 or less optional, but 60 cycles is satisfactory, and as this is a common frequency, it is employed in this combination by me.

Having now described my invention, what I claim as new is—

1. In an electric furnace for the smelting of refractory ores, in combination, a Y connected multiphase source of current supply having a potential wave form, whose front face is comparatively steep, whose top is 90 flat, and whose rear face is upwardly concave, an electrode connected to the free end of each phase, and another electrode connected to the common point of the source, said electrodes being properly spaced so that 95 an arc may be maintained between them.

2. The method of smelting highly refractory metalliferous ores, which comprises subjecting the same to the heating effect of an arc between a plurality of electrodes, 100 supplying a multiphase electric current to said electrodes, said current having a potential whose wave form is such that its front face is comparatively steep, its top is substantially flat, and whose rear is upwardly 105 concave.

3. The method of smelting ores in an electric arc furnace having a plurality of electrodes adapted to be connected to and operated by a Y connected source of polyphase 110 current, which consists in supplying said electrodes with a current whose potential wave form is such that its top is comparatively flat and whose rear is upwardly concave.

4. The method of smelting ores in an electric arc furnace, having a plurality of electrodes adapted to be connected to and operated by a Y-connected source of polyphase current, which consists in supplying 115 said electrodes with a current whose potential wave form is such that its front face is substantially sinusoidal, whose top is flat, and whose rear face is substantially a logarithmic curve.

5. In combination, an electric furnace having a plurality of electrodes adapted to be connected to the several phases of a Y-connected source of polyphase electric current, one electrode adapted to be connected to 130

the neutral point of said phases, and a polyphase generator in which the interaction between the armature windings and the field is such that during the first part of each alternative, the voltage produced follows substantially a sine curve, and then changes abruptly to a flat top, and for approximately the last two-thirds of each alternation the curve follows substantially a logarithmic curve.

6. In combination, an electric furnace having a plurality of electrodes adapted to be connected to the several phases of a Y-connected source of polyphase electric current, one electrode adapted to be connected

to the neutral point of said phases, and a polyphase generator in which the interaction between the armature windings and the field is such that the power factor is substantially one.

7. The method of smelting ores in an electric arc furnace having a plurality of electrodes, which consists in supplying said electrodes with a current whose potential wave form is such that its front face is substantially sinusoidal, whose top is flat, and whose rear face is substantially a logarithmic curve.

In testimony whereof I affix my signature.
GEORGE H. SETHMAN.
